DIAMOND HOLDER

Julius Dinhofe, New York, N. Y.

Application March 31, 1942, Serial No. 437,077

5 Claims. (Cl. 51—229)

This invention relates to holders for diamonds and other gems particularly when the same are to be worked or polished and has for its primary object the provision of means by which the gems may be securely held during the grinding or polishing operation, or for other purposes.

More particularly, the invention contemplates the provision of a stem for reception in a chuck or other holding device, said stem having a seat adjustable extensibly out of one of its ends, and a rotatively adjustable member carrying movable clamping fingers for holding the gem against the seat. The invention further contemplates the provision of means for adjusting the clamping fingers to maintain the same in clamping position to thereby engage and firmly hold diamonds of different sizes against the seat, and also in means by which said fingers and the mounting therefore are capable of fixture in any selected position of engagement with the diamond.

In the accompanying drawing, wherein an embodiment of the invention is shown, Fig. 1 is a side elevation of a diamond holder constructed in accordance with the invention; Fig. 2 is a vertical sectional view through the device; Fig. 3 is a side elevation of the device at right angles to that of Fig. 1, and Fig. 4 is a sectional view on the line 4—4 of Fig. 3, looking in the direction of the arrows.

In the drawing, 1 indicates the stem of the holder, said stem being adapted to be received and held in the chuck of the conventional support for holding the device in the required manner to present the surfaces of the diamond 2, held by it, against the surface 3 of the polishing wheel or other operating structure. Provided in one end of the stem is an internally threaded recess 4 for the reception of a screw 5 having a head 6 constituting a seat for the top surface of the diamond. The top surface of the head, while shown flat to accommodate the top face of the gem, may be recessed or otherwise shaped to fit any other portion of the gem.

Surrounding the stem 1 is a block 7 which is loose on the stem so that the same may be rotatively adjusted thereon and set in any selected position of adjustment by means of the set screw 8. Pivotally mounted at the opposite sides of the block 7 is a pair of fingers 9, each of said fingers being pivoted on a pivot pin 10. The outer ends 18 of each of the fingers is curved inwardly so that these ends of the fingers overlie the top or head of the screw 5 and co-operate therewith in holding the diamond, as clearly shown in the drawing. The inner ends 11 of the fingers are

connected by a torsional coil spring 12 tending to normally draw the inner ends of the fingers toward one another and to resultantly spread the outer or free ends 18 of the fingers apart.

5 Provided on the stem 1 is a threaded portion 13 for the reception of a nut 14 having a circular finger-engaging portion 15 and a conical cam surface 16. The latter surface is operative against the portions 17 of the fingers 9 so that by 10 manual adjustment of the nut 14, the outer ends of the fingers will be caused to move inwardly or toward one another against the tension of the spring 12, and caused to engage against the diamond 2 and clamp the same against the seat 6.

15 The operation of the device is briefly as follows:

The diamond 2 is placed with its top surface against the seat 6, or, if said seat is shaped complementarily to some other portion of the gem, 20 such portion is placed in contact with the seat.

By manipulation of the adjusting nut 14, the fingers 9 are moved to engage the surface of the gem and clamp the same securely against the seat 6. When it is desired to shift the position 25 of the fingers 9 relative to the gem, the set screw 8 is loosened, the block 7 and the fingers 9 carried thereby is rotatively shifted and the set screw is then tightened to hold the block in its new position. Since the screw 5 is adjustably extensible out of the end of the stem 1, it will be 30 obvious that by adjustment of said screw, gems of various sizes may be held in the holder, or the gem may be so positioned in the holder to present more or less of its surface to the grinding or polishing element.

Having described one embodiment of the invention, it is obvious that the same is not to be restricted thereby but is broad enough to cover all structures coming within the scope of the 40 annexed claims.

What I claim is:

1. A diamond holder of the character described comprising, a stem, a block on the same and capable of rotative adjustment on the stem, a seat 45 for one end of a diamond, said seat being adjustably extensible out of one end of the stem, diamond-clamping fingers pivotally mounted in the block and adapted to engage the diamond and clamp the same against the seat, means engaging said fingers and normally tending to separate the end portions of the same, and finger-adjusting means movable axially on the stem for moving the fingers toward one another to cause the same to clamp the diamond against the seat.

55 2. A diamond holder of the character described

comprising, a stem, a seat for abutment against one end of a diamond adjustably mounted in the stem, a block mounted on the stem and adapted for rotative adjustment thereon, a set-screw for maintaining the block in any position of adjustment relative to the stem, a pair of fingers pivotally mounted in said block and adapted to clamp a diamond against the seat, a spring for normally forcing the free ends of said fingers away from each other, and an adjusting element movable axially of the stem for engagement against the fingers to force the free ends of the same toward one another against the tension of the spring.

3. A diamond holder of the character described comprising, a stem having a threaded portion, a seat at one end of the stem and adjustable in and out of the stem, a block rotatively adjustable on the stem adjacent to the seat, means for fixing said block in any position of adjustment, a pair of curved fingers pivotally mounted in the block, said fingers each having a free outer end for engagement against a diamond to clamp the same against the seat, a coil spring surrounding the threaded portion of the stem and connecting the inner ends of the fingers and tending to draw the inner ends of said fingers toward one another, and an internally threaded adjusting nut received on the threaded portion of the stem and movable thereon, said adjusting nut being provided with a cam surface operative against the inner ends of the fingers to force said inner ends of the fingers away from one another against the tension of the coil spring.

4. A diamond holder of the character described comprising, a stem, a screw at one end of the stem having a head forming a seat for the top of a diamond, a block supported on the stem, a pair of fingers pivoted in the block and having free ends for engagement against the under portions of the diamond to clamp the diamond against the seat, spring means engaging the inner ends of the fingers to normally force the free ends of the fingers away from one another, and cam means movable axially of the stem and operative against the fingers to cause the free ends of the same to be moved toward one another against the tension of the spring.

5. A diamond holder of the character described comprising, a stem having a threaded portion, a screw adjustable in one end of the stem, said screw having a head forming a seat against which the surface of a diamond is held, a block on the stem surrounding the screw, a pair of fingers pivoted in the block and having free ends overlying the head of the screw for engagement with surfaces on the diamond to clamp the diamond against the seat, the opposite ends of the fingers extending beyond the block and being connected by a coil spring tending to draw said ends of the fingers toward one another, a nut received on the threaded portion of the stem and adjustable thereon, said nut being provided with a conical cam surface entrant between the spring-connected ends of the fingers to engage against said ends and force the same apart against the tension of the spring which connects them.

JULIUS DINHOFER.
